(57) **CLAIM**

The ornamental design for an electrical bus bar cover, as shown and described.

DESCRIPTION

FIG. 1 is a rear perspective view of an electrical bus bar cover showing our new design;

FIG. 2 is another rear perspective view thereof;

FIG. 3 is a front perspective view thereof;

FIG. 4 is another front perspective view thereof;

FIG. 5 is a rear elevation thereof;

FIG. 6 is a front elevation thereof;

FIG. 7 is a top plan view thereof;

FIG. 8 is a bottom plan view thereof;

FIG. 9 is a left side elevation thereof;

FIG. 10 is a right side elevation thereof;

FIG. 11 is another front perspective view thereof, with environmental structure shown in a partial exploded view; and,

FIG. 12: another front perspective view thereof, with the environmental structure of FIG. 11 shown assembled thereto.

In the drawings, the broken lines depict unclaimed subject matter only and form no part of the claimed design.
